DYEING PROCESS

Lawrence O. Scott, San Jose, Calif.

Application February 18, 1939, Serial No. 257,195

2 Claims. (Cl. 8—146)

The present invention relates generally to the dyeing of fabrics, and more particularly to the dyeing of fabrics without removing or detaching them from the surfaces or articles which they adorn.

While the invention may be susceptible of various applications, particular reference is made to the automobile industry because it is believed that here it has its greatest usefulness.

In order to dye the fabric in an automobile it has heretofore been necessary to remove the same, and because of the expense involved but little of this kind of work is done.

It is, therefore, the object of the present invention to provide a process for dyeing fabrics that will permit the dyeing operation to be performed without removing the fabric from its natural support, and one that will be simple, economical, and highly efficient in its practical application.

In the drawing, the figure is an illustration, partly in elevation and partly in section, showing a means whereby the process embodying my invention may be performed.

The word "dye" in the following specification means any aqueous solution of coloring matter useful in the dyeing of fabrics.

In the preferred embodiment of my invention I provide a boiler 1 in which the liquid dye is placed as at 2, the unoccupied portion of the boiler forming a steam chamber 3. The liquid in the boiler is heated in any suitable manner as by gas applied through the medium of a gas burner placed beneath the boiler as at 4. The boiler is equipped in the usual manner with a gauge as at 5, a pet-cock at 6 and a blowoff valve at 7, the cap 8 being removable to permit insertion of the dye. Connected to the lower portion of the boiler is a hose 9 provided with a shut-off valve 10 and fitted with any desirable form of spray-nozzle as at 11.

In carrying out my invention the dye is heated until steam is formed in chamber 3 and until a steam pressure of some ten pounds, more or less, and a temperature of some two hundred and forty degrees, more or less, is attained. The liquid dye released through nozzle 11 at this high temperature is immediately converted to steam that is forcibly discharged upon the cloth 12 as at 13, contacting the fabric at a slightly lower temperature, probably in the neighbor-

hood of one hundred and ninety to two hundred degrees Fahrenheit.

By introducing the dye into the fabric in this manner the hot steam causes the fibres of the fabric to open up and permit perfect penetration of the dye. In practice I assist the work of the steam by a vigorous brushing of the fabric while the dye is being applied.

I have also found that by carrying out the process as above described but incorporating a cleaning compound in the liquid dye, the cleaning and dyeing of the fabric can be accomplished at the same time. This combining of the cleaner and dye is particularly effective because the action of the cleaner is to dissolve out foreign material from the fabric fibres, and this action prepares the fibres for the immediate reception of the dye. This substitution of the dye for the removable foreign material through the use of a cleaning agent combined with the dye and applied as hereinbefore set forth is the form of the invention most frequently used. In this form of the invention free use of the brush is made while the cleaner and dye is being applied.

While I have herein shown and described but one specific means by which the process may be carried out, various modifications of this means may be employed.

I claim:

30. 1. The process of dyeing fabric which consists in preparing an aqueous solution of a dye, raising the temperature of the dye to a point where it is converted into steam upon contact with the atmosphere, confining said heated solution under pressure greater than atmospheric pressure and forcibly discharging the heated dye by said pressure upon the fabric in the presence of the atmosphere.

35. 2. The process of dyeing fabric, comprising heating a solution of dye, in a closed chamber including a steam space, converting a part of said solution to steam in said steam space to create a pressure in said chamber greater than atmospheric pressure, heating the rest of said solution to a degree where it is converted to steam upon contact with the atmosphere, and discharging the heated liquid part of said solution onto said fabric by said steam pressure in the presence of the atmosphere.
